UNITED STATES PATENT OFFICE.

CHRISTIAN A. EGGER, OF NEW KENSINGTON, PENNSYLVANIA.

RAILWAY-SWITCH.

SPECIFICATION forming part of Letters Patent No. 692,125, dated January 28, 1902.

Application filed October 28, 1901. Serial No. 80,250. (No model.)

To all whom it may concern:

Be it known that I, CHRISTIAN A. EGGER, a citizen of the United States of America, residing at New Kensington, in the county of Westmoreland and State of Pennsylvania, have invented certain new and useful Improvements in Railway-Switches, of which the following is a specification, reference being had therein to the accompanying drawings.

10 This invention relates to certain new and useful improvements in switches, and is particularly adapted to be operated from the moving train or car.

Briefly described, my invention comprises, 15 in connection with the switch-rail and the switch-tongue, a rock-shaft which is journaled underneath the rails and has cam-faces that are alternately brought into contact with the switch-tongue and switch-rail. Throwing 20 rods or bars are connected to the rock-shaft, at each end thereof, and these throwing rods or bars are connected to trips adapted to be engaged by mechanism carried by the moving train or car for actuating the switch so as 25 to place the latter in the desired position.

In describing the invention in detail reference is had to the accompanying drawings, forming a part of this specification, and wherein like numerals of reference indicate corresponding parts throughout the several views, 30 in which—

Figure 1 is a detail perspective view of my improved switch. Fig. 2 is a transverse vertical sectional view of the same. Fig. 3 is a 35 top plan view of a part of the switch, showing the rock-shaft, the throwing rods or bars being removed. Fig. 4 is a detail plan view of the rock-shaft.

To put my invention into practice I employ 40 a switch point or tongue 1 and a switch-rail 2, these being connected together by tie-rods 3 or other suitable means, the switch point or tongue being pivoted at 4 upon one of the cross-ties. The switch point or tongue and 45 switch-rail are preferably laid upon the saddle-plates 5, placed on the cross-ties. A bracket 6 is placed between two of the ties centrally of the road-bed and rigidly secured to said ties, this bracket carrying a bar 7, in which 50 is journaled a rock-shaft 8, the latter being necked down, as at 9, where it is journaled in the bearings 7. This rock-shaft extends be-

yond the rails of the track and carries enlargements or bushings 10 11, having cam-faces 12. These cam-faces are set oppositely to each other, so that when one of same is at the upper side of the rock-shaft the other is at the lower side, and when one is in engagement with the switch-rail 2 the other will be out of engagement with the switch point or tongue, 60 and vice versa. Mounted on the one end of the shaft 8 is a lever 14, the upper end of which is pivotally connected to one end of the throwing rod or bar 15, the other end of this rod being pivotally connected in a trip 16, 65 which is mounted to work in brackets or lugs 17, mounted upon one of the cross-ties. To the lower end of the lever 14 is connected one end of the throwing rod or bar 18, the other end of which is pivotally connected to 70 the trip 19, pivotally mounted in lugs or brackets 17, carried by one of the cross-ties. The opposite end of the rock-shaft has a lever 20 mounted thereon, to the upper end of which is pivotally connected one end of the 75 throwing rod or bar 21, the other end of said rod or bar being pivoted in the trip 22, that is pivotally mounted in brackets or lugs 17, carried by the same cross-tie as the trip 19 is mounted on. To the lower end of the lever 20 is pivotally connected one end of a throwing rod or bar 23, the other end of said rod or bar being pivotally connected to a trip 24, mounted in lugs or brackets 17, carried upon one of the cross-ties. 80

The switch is adapted to be operated by a rod, lever, shoe, or other device (not shown) which is suspended from the locomotive or car. The switch, as shown in Figs. 1 and 2, is set so that the car or train moving on the 90 main track toward the latter will be passed to the side track. In case the car or train moving in this direction desires to continue on the main track the device will be lowered, so as to engage the trip 19 and move the same 95 toward the switch, thus actuating the rock-shaft through the medium of the throwing rod or bar 18, causing the cam 11 to be moved out of engagement with the switch-rail 2 and the cam 10 to be moved into engagement with 100 and forcing the switch point or tongue 1 over into position against the main rail. In case the switch should be closed and the train moving toward the left should desire to enter

the switch the trip 22 will be actuated so as to operate the rock-shaft, causing the cam 10 to be moved out of engagement with the switch tongue or point 1 and the cam 11 to be thrown into engagement with and force the switch-rail 2 against the main rail, removing the switch point or tongue 1 from its contact with the main rail and opening the switch. If the train or car is moving toward the right 10 on the main track, the trip 16 will be engaged so as to actuate the rock-shaft, causing the cam 10 to engage the switch point or tongue 1 and move the latter, together with the rail 2, so as to open the switch. If the train or car 15 is coming off the side track when the switch is closed, the trip 24 will be actuated so as to cause the cam 11 to engage the switch-rail 2 and open the switch to permit the car or train passing onto the main track. The rock-shaft 20 8 is preferably journaled in bearings 6', as well as the bearings 7, these bearings 6' being located underneath the rails of the track.

In practice various changes may be made in the details of construction without departing from the general spirit of my invention.

Having fully described my invention, what I claim as new, and desire to secure by Letters Patent, is—

In combination with the main and side

tracks and a switch-tongue and a switch-rail 30 connected together, a single rock-shaft having bearings located between two of the cross-ties, bushings mounted on said rock-shaft intermediate of its ends, inclined cam-faces on the outer sides of said bushings for engagement with the inner faces of said switch tongue and rail, a lever centrally secured to each end of said rock-shaft on the exterior of the main and side track rails, one of said levers carrying a pair of oppositely-disposed 40 throwing-rods extending in alinement with the main-track rails and having trips carried by their free ends, the other of said levers carrying a pair of oppositely-disposed throwing-rods pivotally secured to its ends, one of 45 said last-named levers extending in alinement with the main track and carrying a trip on its free end, the other of said levers extending in alinement with the side track on the exterior thereof, and carrying a trip on 50 its free end, substantially as described.

In testimony whereof I affix my signature in the presence of two witnesses.

CHRISTIAN A. EGGER.
